PLIERS TYPE WRENCH
John Burton York, 4801 42nd Ave.,
Sacramento, Calif. 95824
Filed Apr. 13, 1966, Ser. No. 549,098
6 Claims. (Cl. 81—361)

The present invention relates to a pliers type wrench and it consists in the combinations, constructions and arrangements of parts hereinafter to be described and claimed, and is a continuation-in-part of my application Ser. No. 349,579, filed Mar. 5, 1964, now abandoned.

Generally there is provided a pliers type wrench having a fixed jaw including a handle to which is pivotally mounted a movable handle having a bifurcated extension. A movable jaw is slidably associated with the fixed jaw and is movable by the aforesaid extension. A pair of semi-cylindrical bearing members are mounted in recesses formed in the movable jaw with their flat faces slidably engaged with opposite sides of a transversely extending projection on the fixed jaw. The device is such that the opposed gripping faces of the two jaws move in parallel relation to each other at all times and provide a secure grip upon all possible sizes of nuts within a wide range including foreign made nuts such as are used on foreign automobiles and the like. The bearing members referred to are offset from one another and assist in maintaining the two jaws of the wrench in parallel relation at all times. A spring normally maintains the two handles and consequently the two jaws apart.

It is accordingly an object of the invention to provide a novel pliers type wrench consisting of a minimum number of parts.

Another object of the invention is to provide, in a device of the character set forth, novel means for maintaining the working jaws thereof in parallel relation to each other at all times.

Still another object of the invention is to provide, in a device of the character set forth, novel bearing members forming a part of the invention.

A still further object of the invention is to provide, in a device of the character set forth, a novel assembly of a fixed and movable jaw which assembly forms a part of the invention.

Another object of the invention is to provide, in a single tool of the character set forth, a device which gives the convenience of a pair of pliers and the holding and gripping power of a wrench.

Other and further objects of the invention will become apparent from a reading of the following specification taken in conjunction with the drawings, in which:

FIGURE 1 is a plan view of an embodiment of the invention illustrating the same in opened condition.

FIGURE 2 is a side elevational view of FIGURE 1,

FIGURE 3 is an end elevational view thereof,

FIGURE 4 is an exploded perspective view illustrating a fixed and a movable jaw both forming parts of the invention,

FIGURE 5 is a view similar to FIGURE 1 but showing the wrench in partially closed condition, and

FIGURE 6 is an enlarged fragmentary plan view of the device illustrated in FIGURE 1 but further illustrating a formula which is utilized in the manufacture of wrenches of the character set forth.

Referring more particularly to the drawings, there is shown therein a wrench of the character set forth having a fixed jaw 10 having an intermediate body portion 11 integral therewith and a rearwardly extending integrally formed handle 12.

A movable jaw 13 is provided on its inner face with a transverse groove 14. A circular opening 15 extends

2

through the movable jaw 13 centrally of the groove 14. At each side of the groove 14 the movable jaw 13 is provided with a substantially semi-circular recess 16 for the slidable reception therein, in each case, of a semi-cylindrical bearing member 17 the flat surface of which, in each case, is presented inwardly with respect to the groove 14. The movable jaw 13 is provided with an enlarged gripping head 18 while the fixed jaw 10 is likewise provided with an enlarged gripping head 19.

10 The fixed jaw 10 is provided with a transversely extending integrally formed inwardly directed boss 20 the parallel side faces of which are adapted to bear against the flat faces of the bearing member 17 when the device is in assembled condition.

15 A transverse slot 21 is formed in the fixed jaw and extends centrally through the boss 20.

A movable handle 22 of U-shaped cross sectional area encompasses the handle 12, the intermediate portion 11 and both of the jaws 10 and 13 is pivotally connected to the rearward end portion of the intermediate portion 11 by means of a bolt and nut 23 or the like. Both sides thereof are provided with a relatively short longitudinally extending slot 24 adjacent the forward end thereof and a bolt and nut or like member 25 extends through the slots 24, the opening 15 and the slot 21.

20 A spring 26 has one of its ends mounted in a transverse opening 27 in the handle 12 adjacent the pivotal point 23 and has its larger end portion, indicated at 28, bearing against the inner side of the bight portion of the 30 movable handle 22.

In the present invention, certain relative dimensions are of vital importance and should be considered as a part of the invention. I have derived a formula which will assist a manufacturer in constructing the wrench of the present invention in such manner that it will have sufficient holding power and yet will not have intolerably high stresses. The formula is:

$$E = .2A + .1B$$

35 In the formula E is the distance from the center of one bearing to the center of the other bearing in the direction of jaw travel. A is the distance from the rear end of the nut engaging jaw faces to the face of the nearest bearing member in a direction parallel to the jaw faces.

40 B is the distance between the faces of the bearing members in a direction parallel to the jaw faces. These elements are indicated graphically in FIGURE 6. Also, C is the minimum jaw opening.

The depth of the bearing members parallel to the jaws is very important. To increase the depths of these members would tend to rotate the movable jaw inward and might decrease E by as much as four times the change in the bearing member depths. To decrease the bearing member depths would have an opposite effect. Therefore,

45 after the principal parts of a wrench have been made in accordance with the formula, bearing member sizes should be selected which will cause the jaws to be parallel when a nut is tightly engaged. In construction slight errors may be made in the widths of boss 20 and groove 14. Correct selection of bearing member sizes will nullify such errors.

50 It will be noted that the two points of resistance to rotation of the jaws relative to each other are the centers of the two bearing members 17. These two points may be at any desired distance apart. However, the two points of resistance in a given wrench of this type will remain the same distance apart as the movable jaw travels toward and away from the fixed jaw. It will be apparent that the bearing stresses will be distributed uniformly over the

55 entire flat bearing surface of each of the bearing members 17 and it will also be seen that the development of large loads without intolerably high stresses is ac-

complished by the use of bearings having arcuate faces mounted in arcuate openings as above described thus allowing the bearings free rotation in their niches to thereby equalize the load.

In operation, it will be apparent that as the movable handle 22 is moved toward the fixed handle 12 by the customary hand gripping of the same, that the forward portion of the handle 22 will move the pivot member 25 to the left as viewed in FIGURES 1 and 5 thus causing the pivot member 25 to move upwardly in the relatively short groove 24 and to the left in the relatively long groove 21 in the fixed handle. During this process, it will be apparent that the bearing members 17 will have their inner or flat faces in bearing relation to the sides of the boss member 20 thus enforcing the movable jaw 13 and consequently the gripping heads 18 and 19 to remain in constant parallel relation to each other. The arcuate rear faces of the bearing members 17 will assist in properly aligning the flat faces thereof with the flat faces of the boss member 20.

While but one form of the invention has been shown and described herein, it will be readily apparent to those skilled in the art that many minor modifications may be made without departing from the spirit of the invention or the scope of the appended claims.

What is claimed is:

1. A wrench comprising fixed and movable jaws, one of said jaws having a boss extending transversely from the inner face thereof, and the other of said jaws having a transverse groove therein for the slidable reception of said boss, said jaws having openings therethrough, a rigid handle on one of said jaws, and a movable handle pivoted to said first mentioned handle, a slot in the inner end portion of said movable handle, and a pivot member extending through each of said openings, an arcuate bearing member rotatably mounted in one of said jaws at each side of said groove, said bearing members each extending partially into said groove and presenting their flat faces in abutting relation to opposite sides of said boss.

2. A wrench comprising a fixed jaw, a boss extending transversely from the inner face of said fixed jaw, a movable jaw having a transverse groove therein for the slidable reception of said boss, said fixed jaw having a transverse slot formed therein and extending centrally through said boss, said movable jaw having an opening therethrough, a handle formed integrally with said fixed jaw, a bifurcated movable handle pivoted to said first men-

tioned handle, a pair of longitudinal slots in the inner end portion of said movable handle, and a pivot member extending through said opening and said longitudinal and transverse slots, a semi-cylindrical bearing member rotatably mounted in said movable jaw at each side of said groove, said bearing members each extending partially into said groove and presenting their flat faces in abutting relation to opposite sides of said boss.

3. A device as defined in claim 2 wherein said bearing members are in staggered relation to the longitudinal axis of said movable jaw.

4. A device as defined in claim 3 wherein said jaws are each provided at their outer end portions with a laterally enlarged gripping head, said heads being in opposed relation to each other.

5. A device as defined in claim 4 wherein a spring has one of its end portions mounted in said fixed handle and its other end portion bearing against the inner side of said bifurcated movable handle.

6. A wrench comprising a fixed jaw with a boss extending therefrom, a movable jaw with a groove transversely slidably associated with said fixed jaw, a handle integrally connected to said fixed jaw, and a movable handle pivoted to said first mentioned handle and slidably and pivotally connected to said movable jaw, a semi-cylindrical bearing member rotatably mounted in said movable jaw

at each side of said groove, said bearing members each extending partially into said groove and presenting their flat faces in abutting relation to opposite sides of said boss, said bearing members being in staggered relation to the longitudinal axis of said movable jaw, said jaws being each provided at their outer end portions with a laterally enlarged gripping head, said heads being in opposed relation to each other.
